UNITED STATES PATENT OFFICE.

LEON M. GIROUX, OF NEW YORK, N. Y.

LAMP.

1,243,930.

Specification of Letters Patent. Patented Oct. 23, 1917.

Application filed February 28, 1917. Serial No. 151,386.

To all whom it may concern:

Be it known that I, LEON M. GIROUX, a citizen of the United States, and a resident of New York, in the borough of Manhattan, county of New York, and State of New York, have invented certain new and useful Improvements in Lamps, of which the following is a specification.

This invention relates to improvements 10 in and relating to lamps, and particularly lamps for automobiles, aeroplanes, motor boats, or the like. An object of the invention is to provide a lamp of this character which will be artistic in appearance, of such 15 shape as to form practically no resistance to the wind, and having lines which harmonize with the well-known stream line type of car, thereby giving an added appearance of speed and grace to such cars. 20 Another object is to provide in such a lamp, lighting means by which light may be disseminated and reflected in all directions therefrom, and to this purpose, I propose to provide an opening at the front, openings 25 extending radially around the body of the lamp, and an opening at the rear, all provided with suitable lens, colored glass and the like, and a lighting means whereby light may be reflected in all directions 30 through the various openings.

With these and other objects in view, embodiments of my invention are shown in the accompanying drawings, and these embodiments will be hereinafter more fully 35 described with reference thereto, and the invention will be finally pointed out in the claims.

In the drawings,

Figure 1 is a side elevation of my im- 40 proved lamp;

Fig. 2 is a sectional view thereof;

Fig. 3 is a modified form of construction;

Fig. 4 is a section on the line 4—4 of Fig. 2, and

Fig. 5 is a section on the line 5—5 of Fig. 3.

Similar reference characters indicate corresponding parts throughout the several views.

Referring to the drawings, and more particularly to Figs. 1 and 2 thereof, my invention comprises a body portion formed in two sections 10 and 11, the section 10 being provided with external screw threads, and

55 the section 11 with an internally screw

threaded flange, which is screwed into the section 10 for securing the sections together. In the form illustrated, the general contour of the lamp is bullet or torpedo shaped, but this it will be understood may be changed as desired. The forward portion of the member 10 has an inwardly tapering tubular member 12, arranged therein, at the ends of which are mounted the lens 13 and 13^a, and a reflector 14 is provided at the rear of the said member, a lamp socket 15 being secured centrally of the said reflector. An electric incandescent lamp 16 is provided in the said socket, and current is supplied to the same by means of wires 17, which extend at the rear of the reflector 14 through the sides of the lamp, and a bracket 18 provided on the lamp for securing the same to the automobile or other vehicle.

75 Radially arranged in the sides of the lamp about the incandescent lamp 16 are a plurality of longitudinally disposed openings 19 suitably spaced apart and provided with glass inserts 20, which may be red, blue, or any desired color. These may also be in the form of bull's-eyes, but the elongated shape is preferred, as this gives the desired appearance of speed and also more effectively distributes the light rays. An- 80 other opening 21 is provided in the end of the member 11, in which is inserted a glass piece 22, through which light rays are di- 85 rected from the incandescent lamp 16 by means of apertures 23 provided in the re- 90 flector 14. This clearly defines the length and appearance of the lamp at night, and also indicates to anyone at the rear of the lamp that the same is lighted.

95 The foregoing construction is particularly adapted for the side-lights of automobiles, but in Fig. 3 I have shown a form of my invention to be used as a headlight. The general shape and arrangement of the lens and glass inserts are practically the same 100 as in my first construction, but a reflector 24 is arranged immediately behind the front lens 25, both the lens and the reflector being held in place by means of a ring 26 threaded or otherwise suitably secured to the front 105 of the lamp. A lamp socket 27 is secured centrally of the reflector in which is secured an electric incandescent lamp 28, and behind the same is arranged a second incandescent lamp 29 mounted in a socket 30 at the rear 110.

of the reflector and held in position by a bracket 31. The lamp 29 reflects light through the openings in the sides and in the end of the lamp. The wires 32 for both 5 incandescent lamps pass through the side of the lamp and through a bracket 33 for supporting the same.

With the use of my improved construction, a very attractive lamp is provided by 10 which a great amount of light is given by means of a very small amount of lighting power, and the lamp is clearly visible in all directions. At the same time, the elongated lens in the side of the lamp, together with 15 the tapering to the rear portion of the small rear lens 22, gives an appearance of great speed and grace.

I have illustrated and described preferred 20 and satisfactory embodiments of my invention, but it is obvious that changes may be made therein within the spirit and scope thereof, so that I do not wish to be limited to the particular form shown except as may be required by the claims.

25 I claim:

1. A lamp of the character described comprising an elongated casing tapered toward one end and provided with a lens at one end and with a circular series of translucent 30 prisms peripherally disposed around its body portion, and an electric lamp socket mounted in said casing and adapted to hold a lamp bulb opposite said peripheral prisms in position to emit light rays forward through 35 said lens and radially through said prisms around said body.

2. A lamp of the character described comprising an elongated casing tapered toward one end and provided with a lens at one 40 end and with a circular series of translucent prisms peripherally disposed around its body portion, an electric lamp socket mounted in said casing and adapted to hold a lamp bulb opposite said peripheral prisms in position 45 to emit light rays forward through said lens and radially through said prisms around said body, and a convex reflector back of

said circular series of prisms and adapted to reflect rays therethrough.

3. A lamp of the character described comprising an elongated casing tapered toward one end and provided with a lens at one end and with a circular series of elongated translucent prisms peripherally disposed around its body portion, and an electric 55 lamp socket mounted in said casing and adapted to hold a lamp bulb opposite said peripheral prisms in position to emit light rays forward through said lens and radially through said prisms around said body. 60

4. A lamp of the character described comprising an elongated casing tapered toward its rear end and provided with lenses at its opposite ends and with a circular series of translucent prisms peripherally disposed around its body portion, and an electric lamp socket mounted in said casing and adapted to hold a lamp bulb opposite said peripheral prisms in position to emit light rays forward and rearward through said lenses and 70 radially through said prisms around said body. 75

5. A lamp of the character described comprising an elongated casing tapered toward one end and provided at its tapered rear end with a lens and at its front end with an inwardly projecting tapered lens tube having a large convex lens at its front end and a small convex lens at its rear end and around its body with a circular series of 80 translucent prisms, and an electric lamp socket mounted in said casing and adapted to hold a lamp bulb opposite said peripheral prisms in position to emit light rays forward and rearward through said lenses and 85 radially through said prisms around said body.

In testimony, that I claim the foregoing as my invention, I have signed my name in presence of two subscribing witnesses.

LEON M. GIROUX.
